BLOW SWITCH OPERATED TOY

Heinrich Müller, Nuremberg, Germany

Application September 17, 1937, Serial No. 164,400
In Germany August 2, 1937

14 Claims. (Cl. 46—208)

This invention relates to blow switch operated toys and more particularly to toys of this kind having the form of a toy-vehicle provided with spring-driven clockwork and a blow switch as had been described and claimed in a co-pending application for Letters Patent Serial No. 130,778, filed by me on the 13th of March 1937 and consists essentially in a further improved construction of said toy-vehicle.

More particularly, my invention is concerned with a special improvement provided on a blow switch operated toy of the aforementioned kind; said toy including a transmission-gearing having a locking gear-wheel which is intermittently rotated upon actuation of a membrane forming part of said blow switch, in such a manner that alternately a tooth or an interstice between adjacent teeth moves into the path of rotation of a stop-lever fast on a driven member of the spring-driven clockwork.

Owing to the peculiar operation of blow switches for the control of the clockwork of toys or toy-vehicles, the operation of switching must take place essentially without moving masses as otherwise there would be required relatively large forces for overcoming the inertia. For this reason, the membrane of the blow switch must be made from rather thin and light material which accordingly is of but little mechanical strength. In order to provide for safe and permanent operation of the blow switch and for effective control of the clockwork of the toy, according to my invention the membrane of the blow switch is covered up by a protective grid or grate which prevents said membrane against being touched by the hand of the person playing with the toy and, in addition, permits proper and effective access of the current of air to said membrane to operate said blow switch. In accordance with this, the operation of said membrane underneath said grid or grate will be effected in a manner to be concealed from the eyes of the person or persons playing with the toy or of onlookers.

Since in this case it should also be possible to initiate the switching operation by hand, according to my invention I further provide, in addition to the blow switch, a hand-lever mounted to project out of the casing of the toy, preferably at the place of said grid or grate, to a sufficient extent to permit of being easily actuated, for instance by touching the same with a finger.

In addition to the aforementioned two main novel features of my present invention I provide a special construction and arrangement of the blow switch and especially of its membrane,

as more fully described herein and pointed out in the appended claims, said novel construction and arrangement serving to effect with a greater degree of certainty proper action of said membrane as well as proper control of the clockwork and of the toy as a whole.

Besides, I further provide possibilities for the blow switch to permit proper operating motion thereof within the casing of the toy, without, however, in any way impairing the appearance of the latter.

Although the blow switch represents a mechanism requiring adequate co-operation with the transmission-gearing to secure proper control and operation of the toy, no special work of precision will be necessary and the construction of the toy and its parts may be made of very simple construction.

In the accompanying drawing, I have shown my improved blow switch operated toy forming part of my present invention, Fig. 1 being a longitudinal section of the toy; Fig. 2 a top-view taken on Fig. 1 with partly broken-away casing; Fig. 3 a partial side-view of the spring-driven clockwork together with the transmission-gearing and the hand-lever associated therewith; Fig. 4 an enlarged partial view of said transmission-gearing as seen in direction from the clockwork; Fig. 5 a partial side-view, partly in section, and Fig. 6 a front-view of said transmission-gearing.

Referring now more particularly to the drawing, the spring-driven clockwork 1 of the toy is mounted within the casing thereof, the frame of the clockwork carrying a bearing-axle 2 on which the membrane of the blow switch is shown as a double-armed lever carrying at its front end 3 a locking and releasing member 11 extending into a small and properly bent wire 28, while at its rear part said double-armed lever carries the membrane or blow-surface 4 having the form of a flat or preferably depressed plate in which latter case also a rim may be provided round said plate. Said membrane or plate 4 of the blow switch is mounted within the casing of the toy underneath a number of perforations or slits 5 provided therein. Said membrane 4 of the blow switch will thus be protected and concealed within the casing of the toy, while at the same time said perforations or slits will permit access of a current of air to said membrane 4 to operate the blow switch. The edges of said perforations or slits 5 are preferably bent towards the inside of the casing, so that said perforations or slits as a whole will have the appearance of a grid or grate.

provided in said casing above said membrane 4 of the blow switch.

The blow switch which is mounted to permit sufficient operating motion may be operated by a current of air blown through said grid or grate formed by said perforations or slits 5 without in any way impairing the appearance of the toy or necessitating any undesirable changes thereon.

In view of the fact that the blow switch is concealed from view, being positioned within the casing, according to my invention I also provide means permitting to operate said blow switch by hand. For this purpose I further provide on the aforesaid bearing-axle 2 a hand-lever 6, the upper end thereof extending somewhat above said grid or grate 5 on the casing, while the under part of said lever 6 carries a counter-weight 7 and is guided within the body of the toy.

The hand-lever 6 in the example described herein and shown in the drawing extends with its upper end or handle through an aperture in said double-armed lever which forms part of said blow switch and is provided with a projection or nose 15 positioned underneath the front arm 3 of said double-armed lever and adapted to lift said arm 3 upon depression of said hand-lever 6, to effect an additional manual control of the blow switch. Moreover, by action of the counter-weight 7 the hand-lever 6 upon being released will at any time again move automatically into inoperative position as indicated in Figs. 1 and 3.

The hand-lever 6 with its counter-weight 7 does not need to positively co-operate with the blow switch, it being also within the scope of my invention to arrange said hand-lever to lock and release immediately and independently of the blow switch the transmission-gearing comprising a switch-wheel 27 and a crown-wheel 26 both mounted rotatably at the front of the clock-work 1.

In the one as well as in the other case the hand-lever 6 with its counter-weight 7 is constructed and mounted to perform the function of a mechanically independent control-member and remains inoperative, whenever the membrane 4 of the blow switch is deflected subsequent to being actuated by a current of air passing through the grid or grate in the casing of the toy.

The transmission-gearing, more particularly, consists of a locking gear-wheel 26 in form of a crown-wheel having preferably rectangular teeth and accordingly rectangular interstices therebetween, and of a switch-wheel 27 in the form of an ordinary toothed wheel, said wheels being either integral or, as shown in the drawing, fixedly connected with each other.

The aforementioned wire 28 fast on lever-arm 3 of the blow switch co-operates with the teeth on the periphery of the switch-wheel 27, said wire 28 more particularly being supported within the inwardly bent edges of the arm 3 of the double-armed blow switch lever. The somewhat longer upper portion 11 of wire 28 co-operates with the interstice between the teeth of the switch-wheel 27 to form a locking pawl therefor, as may be seen especially from Figs. 4 and 6. Moreover, the wire 28 supported by the arm 3 of the blow switch lever extends with its under bent end co-operating with the switch-wheel 27 through a properly shaped aperture 14 in a bearing-bridge 12 mounted in front of the casing of the clock-work 1. This aperture 14 in said bearing-bridge 12 serves to limit the operating stroke of the wire 28 in upward direction, therewith simulta-

neously fixing the swinging motion of the blow-switch lever within the casing of the toy, without making use of the weak and thin membrane 4 of the blow switch for this purpose.

The crown-wheel 26 which forms part of the transmission-gearing serves to control a stop-lever 13 consisting preferably of a resilient finger or wire fast on an axle 9 of the clockwork 1, said axle 9 being preferably provided with a wind-plate, if this axle is the last one of the clockwork. In case said stop-lever 13 consists of a wire it may preferably be fixed to the axle 9, by winding said wire around said axle with a few turns as shown particularly in Fig. 4. If now an interstice between the teeth of the crown-wheel 26 is positioned within the path of motion of said stop-lever 13, the clockwork will be released to effect travelling motion of the toy. On the other hand, if a tooth of said crown-wheel 26 is positioned within the path of rotation of said stop-lever 13, rotation of the latter will be stopped to lock the clockwork and cause standstill of the toy. The alternate position of a tooth or of an interstice between teeth of the crown-wheel 26 within or out of the path of rotation of said stop-lever 13 may thus be controlled at will either by actuating the blow switch by means of a current of air blown against the membrane 4 or by actuating said hand-lever 6. During such switching the front arm 3 of the double-armed lever of the blow switch will lift the wire 28 to engage with a tooth of the switch-wheel 27 so as to impart a short partial rotation to the latter and therewith also to the crown-wheel 26, so that within the path of rotation of the stop-lever 13 there will either be an interstice or a tooth of the crown-wheel 26, thus to permit rotation of said stop-lever 13 or to stop the latter, respectively.

Upon repeated actuation of the blow switch, therefore, the stop-lever 13 and therewith the clockwork may alternately be released or stopped to cause travel or standstill of the toy.

As the front arm 3 of the double-armed lever of the blow switch is somewhat heavier than the rear part 4, the blow switch will automatically assume its normal position shown in the drawing subsequent to every switching motion. The membrane 4 forming part of the blow switch will effectively catch the current of air blown thereagainst, especially if said membrane is of depressed conformation or provided with a rim, which will favorably assist and act upon the switching operation. Switching, however, may not only be effected by actuation of the blow switch, but also by actuation of the hand-lever 6, as desired, the latter acting either by way of the blow switch or also immediately onto the transmission-gearing as had above been described. Manual control of the toy may thus be effected with certainty, as the blow switch itself is positioned underneath the protecting grid or grate in the casing of the toy and thus prevented against being immediately operated by hand or by pressure exerted thereonto by a finger.

The operation of switching as well as the mode of operation of the toy will be all the more interesting by providing the aforescribed hand-lever in addition to the blow switch, because by this there will be given the possibility of stopping operation of the toy during winding-up the clock-work by depressing the hand-lever without actuating the blow switch.

Thus, the attention of a person who is not familiar with the peculiar construction and op-

eration of my present toy will be distracted from the fact that the operation of the clockwork of the toy may be initiated or stopped, besides by depressing the hand-lever, by speaking or blowing 5 against the blow switch.

As the upper arm 11 of the locking and releasing wire 28 carried by the front end 3 of the blow switch lever locks the transmission-gearing when engaging with the switch-wheel 27, the bearing 10 axle 26 of the transmission-gearing is of a relatively large diameter with the result that a large surface friction will arise between said axle and the bearing-bridge 12, this friction on account 15 of its braking action assisting in the stopping of the freely rotatable transmission-gearing.

The blow switch may also be constructed in form of a single-armed lever instead of in the form of a double-armed lever as shown in the drawing, it being only essential in the sense of 20 my invention that this switch is provided with a locking and releasing member 28 including a pawl which serves to engage or disengage the transmission-gearing.

My present toy may further be equipped with 25 a reversing device permitting alternate forward or rearward travel of the toy. Such a reversing device may be constructed in the form of a slide which may be drawn out of the body of the toy, as indicated at 40 in the drawing. In this case, 30 the blow switch forming part of my present toy is of course so arranged that it will act in like efficient manner during forward as well as during rearward travel of the toy.

I claim:

1. A toy, comprising a clockwork and double control means therefor, said double control means consisting of a blow switch and of a hand-lever, either means being adapted to lock or release said clockwork.

2. A toy comprising a clockwork, a blow switch, 40 and a transmission-gearing intermediate said blow switch and said clockwork, said transmission-gearing being under control of said blow switch to alternately release and lock said clockwork, and a protective grid or grate for said blow switch to prevent touching of said blow switch by-hand, but to permit access of a current of air through said grid or grate for actuating said blow switch.

3. A toy as specified by claim 2, including, in 50 addition to the blow-switch, a hand-lever adapted to lock or release said transmission-gearing and therewith said clockwork independently of said blow switch.

4. A toy as specified by claim 2, including a 55 casing in which said protective grid or grate is provided by perforations, slits or the like.

5. A toy as specified by claim 2, including, in 60 addition to the blow switch, a hand-lever adapted to lock or release said transmission-gearing and therewith said clockwork, said hand-lever being in operative connection with said blow switch to act onto said transmission-gearing by way of said blow switch.

6. A toy as specified by claim 2, in which the 65 blow switch consists of a membrane carried by

a swingable lever and of a locking and releasing member connected thereto to lock and release a switch-wheel forming part of said transmission-gearing upon actuation of said blow switch.

7. A toy as specified by claim 2, in which the 5 blow switch consists of a membrane carried by a swingable lever and of a locking and releasing member connected thereto to lock and release said transmission-gearing upon actuation of said blow-switch, said locking and releasing member 10 being further adapted to limit the swinging motion of said membrane.

8. A toy as specified by claim 2, in which the transmission-gearing includes a gear-wheel adapted to lock and release a finger mounted on 15 an axle forming part of the clockwork.

9. A toy as specified by claim 1, including a transmission-gearing controlled by said double control means, said transmission-gearing comprising a locking and releasing gear-wheel 20 adapted to alternately stop or release a lever fast on a driven axle of said clockwork.

10. A toy as specified by claim 1, in which the blow switch consists of a swingably mounted single-armed lever and of a membrane carried 25 thereby.

11. A toy as specified by claim 1, in which the blow switch consists of a membrane swingably mounted on a double-armed lever, one arm of 30 said lever carrying a membrane and the other arm a locking and releasing member for the clockwork.

12. A toy as specified by claim 1, including a transmission-gearing interposed between said double control means, said transmission-gearing 35 comprising a switch-wheel, a locking and releasing wheel and a bearing axle for both of said wheels, said bearing axle having a relatively large diameter to produce a relatively large surface-friction for said wheels, thus to assist locking 40 thereof when freely rotating.

13. A toy of the self-propelled type including a spring motor therefor, a pivotally mounted breath responsive control member, a pawl, a ratchet wheel, cooperating with said pawl and rotated thereby step by step by successive impulses imparted to said control member, a member rotatable by said spring motor and means responsive to the step by step movement of said ratchet wheel for alternately blocking and unblocking the rotation of said rotatable member, 50 whereby successive impulses on said control member will cause alternate arrest and release of said spring motor.

14. A toy comprising a casing, a clockwork in 55 said casing, double control means for said clockwork, said double control means consisting of a blow switch and of a hand lever, either means being adapted to lock or release said clockwork, and a protective grid or grate for said blow switch 60 formed by perforations, slits or the like in said casing, to prevent touching of said blow switch by hand but to permit access of a current of air through said grid or grate for actuating said blow switch.

HEINRICH MÜLLER. 65
